UNITED STATES PATENT OFFICE.

ALBERT SCHMID, OF NEW YORK, N. Y.

CHARGE-FORMING DEVICE FOR INTERNAL-COMBUSTION ENGINES.

1,369,551.

Specification of Letters Patent. Patented Feb. 22, 1921.

Application filed January 10, 1918. Serial No. 211,271.

To all whom it may concern:

Be it known that I, ALBERT SCHMID, a citizen of the United States, and a temporary resident of the Hotel Biltmore, New York, in the county of New York and State of New York, have made a new and useful Invention in Charge-Forming Devices for Internal-Combustion Engines, of which the following is a specification.

- 10 This invention relates to charge forming devices for internal combustion engines and more particularly to devices for forming combustible charges for starting and during the warming up periods.
- 15 The use of heavy not readily inflammable liquid fuels such as kerosene and distillates and so called commercial gasoline in internal combustion engines and especially in engines subject to varying loads makes it im-
- 20 portant that some means be provided by which readily combustible charges may be supplied during the warming up periods or until the engine and its inlet manifold become warm enough to care for the combustible charges supplied by the main charge forming device or carbureter.
- 25

Finding that it is impracticable to heat the main carbureter, either by electricity or other means, sufficiently to take care of the carbureter during the warming up periods an object of this invention is to provide a supplemental or auxiliary charge forming device by means of which (during the warming up periods and until the engine is sufficiently warm to be operated upon the main carbureter) readily combustible charges may be supplied.

A further object is to provide an efficient electrically heated device of this character which may be utilized in conjunction with any of the well known types of carbureters and which with a relatively small consumption of electric energy will effectively heat the fuel content of the starting charges so that when the charges reach the engine cylinders they will be readily inflammable and will burn with a minimum amount of objectionable deposit or smoke.

These, as well as other objects which will readily appear to those skilled in this art, I attain by means of the device illustrated in the drawings accompanying and forming a part of this application.

In the drawings, Figure 1 is a sectional elevation of a charge forming device embodying this invention, Fig. 2 is a cross sec-

tional view of the same, and Fig. 3 is a view in side elevation of a portion of the inlet manifold of an internal combustion engine to which a main carbureter is attached and 60 also to which an auxiliary or starting carbureter embodying this invention is shown applied.

The device consists essentially of an electrically heated tortuous passage through 65 which the fuel content of the combustible charges (or the fuel content and a small amount of air) is caused to pass at high velocity, a fuel nozzle, an auxiliary air nozzle, and means for controlling these nozzles. 70

The form of device shown in the drawings consists of a spirally wound resistance ribbon 4 contained within a chamber formed of a cup shaped member 5 preferably made of insulating material such as soap stone 75 and a cover plate 6 of the same material. The heater made up of the ribbon and the housing members 5 and 6 lies within an annular chamber formed in a casting 7 and a cover plate 8 is threaded into the housing 80 at 9 retaining the heater elements in proper position.

The resistance ribbon and cupped member 5 are secured in housing 7 by means of screws 10 which pass through insulating 85 bushings 11 and into the side of the housing 7. A binding post 12 which connects with the resistance ribbon through connection 13 and said screws is connected up to a suitable source of electrical supply such as a storage 90 battery 14 by means of circuits 15 controlled by switch 16.

Liquid fuel for making up the fuel content of the combustible charges is supplied to the spiral passage formed by the resistance 95 ribbon by means of a nozzle 17 rendered adjustable by means of a needle valve 18. Liquid fuel for the charges is supplied from a float controlled chamber 19 or may be derived directly from any suitable source of 100 supply. A plunger 20 slidably mounted within a cylinder 21 axially aligned with nozzle 17 carries a valve 22 for controlling the effective area of adjusted nozzle 17 and a spring 23 surrounding the stem 24 of the 105 plunger tends to yieldingly force valve 22 to its seat in nozzle 17 to close off the liquid fuel supply, or throttle the same more or less.

Liquid fuel supplied by nozzle 17 passes 110 into the tortuous passage formed by the resistance ribbon through an inlet 25 which

registers with an inlet opening formed in one wall of the cupped member 5. If found desirable a restricted air inlet 26 may be provided in the wall of chamber 21 adjacent the outlet of nozzle 17 for supplying a small amount of air with the fuel traversing the passage through the heater.

The passage of fuel or fuel and air into the heater is controlled by plunger 20, which, when nozzle 17 is closed cuts off communication between the nozzle chamber and the interior of the heater. An auxiliary air nozzle or inlet 27 is provided for mixing proper amounts of air with the heated fuel to form combustible charges. The auxiliary inlet is controlled by means of a plunger valve 28 provided with openings 29 for registering with openings 27. The combustible charges passing through the heater emerge therefrom through an outlet opening 30 formed in a hollow central boss carried by wall 31 of the casting 7. This boss also serves as a support for the inner end of the resistance ribbon.

The air admitted through inlets 27 mingles with the vaporized fuel stream at point 32 and passes to the inlet manifold 33 of the engine through an opening in said manifold which registers with the outlet 34.

Since it is desirable to simultaneously control nozzle 17 and supplemental air inlets 27 I provide a double armed rock lever 35 pivotally mounted on an arm 36 extending from the main casing of the device, and arm 37 which operatively connects with stem 24 of plunger 20 is adapted to open nozzle 17 as arm 38 moves downward to open auxiliary air inlets 27. By this means the nozzle and supplemental air inlets are opened simultaneously and in the same proportions.

As the charges necessary for starting up an internal combustion engine are relatively small this device may be relatively small, and, by making the cross section of the several convolutions of the heater passage small the velocity of the stream passing therethrough is relatively high. This high velocity causes the fuel in passing through the heater to be projected by centrifugal force and impinged against the heated coils whereby it is thoroughly broken up into a mist and efficiently heated to a relatively high temperature.

By restricting the amount of air passing through the heater with the fuel to the smallest possible amount the amount of current necessary to raise the fuel to the proper temperature is materially decreased. The more air that is admitted with the fuel the greater will be the amount of current necessary to

raise the fuel to a given temperature. The heated fuel stream issues from outlet 30 in the form of a highly heated fuel mist, and, by means of the air admitted through auxiliary air inlets 27 is swept on to the engine inlet manifold and from there to the engine cylinders which it reaches in a highly inflammable state.

In operating the device it will be understood that the throttle valve 40 of the main carburetor 41 will be closed so that all of the combustible charge used is formed by the auxiliary or supplemental charge forming device. As soon as the engine to which the device is attached is sufficiently warm to care for the charges formed by carburetor 41 the device may be cut out of operation by closing the fuel nozzle 17 and auxiliary air inlet ports 27.

It will be understood that the device illustrated is more or less diagrammatic and that in actual practice the principles thereof may be embodied in various forms.

Having thus described my invention what I claim is—

1. In a charge forming device for internal combustion engines, a spiral passage of relatively small cross section and relatively great length, means for electrically heating said passage, means for admitting a mixture of liquid fuel and air to said passage, means for mixing air with the mixture issuing from said passage, and means for controlling the fuel admitted to said passage and the air mixed with the mixture issuing from said passage. 95

2. In a charge forming device for internal combustion engines, a passage formed from a spirally positioned ribbon of resistance metal and insulating side plates, means for admitting a mixture of liquid fuel and air to said passage, means for mixing air with the mixture stream issuing from said passage, and means for controlling the fuel admitted to said passage and the air mixed with the mixture issuing from said passage. 100

3. In a charge forming device for internal combustion engines, a spiral passage of relatively small cross section and relatively great length formed by confining a spirally wound ribbon of resistance metal between disks of insulating material. 110

In testimony whereof, I have hereunto subscribed my name this 4th day of January, 1918.

ALBERT SCHMID.
